Primary Examiner — Susan E Krakower*Assistant Examiner* — Lisa A Grabenstetter(74) *Attorney, Agent, or Firm* — Foley & Lardner LLP(57) **CLAIM**

I claim the ornamental design for a bag, as shown and described.

DESCRIPTION

FIG. 1 is a front perspective view of a bag of the claimed design;

FIG. 2 is a front elevational view of the bag shown in FIG. 1;

FIG. 3 is a rear elevational view of the bag shown in FIG. 1;

FIG. 4 is a right side elevational view of the bag shown in FIG. 1;

FIG. 5 is a left side view of the bag shown in FIG. 1;

FIG. 6 is a top plan view of the bag shown in FIG. 1;

FIG. 7 is a bottom plan view of the bag shown in FIG. 1; and, FIG. 8 is a front elevational view of the bag shown in FIG. 1 with the handle in an alternate configuration.

The dashed lines in the figures represent stitching and are part of the claimed design.
